UNITED STATES PATENT OFFICE

131,350

DESIGN FOR A ROASTING OR BAKING PAN

Styles T. Howard, Jeffersonville, Ind.

Application June 4, 1941, Serial No. 101,299

Term of patent 3½ years

To all whom it may concern:

Be it known that I, Styles T. Howard, a citizen of the United States, residing at Jeffersonville, Indiana, have invented a new, original, and ornamental Design for a Roasting or Baking Pan, of which the following is a specification, reference being had to the accompanying drawing forming a part thereof.

Fig. 1 is a perspective view of the roasting or baking pan showing my new design, with the lid raised; and

Fig. 2 is a back elevational view thereof, illustrating the side not seen in Fig. 1, with the lid in place.

I claim:

The ornamental design for a roasting or baking pan, substantially as shown.

STYLES T. HOWARD.
